INVISIBLE SCREW SHOWCASE BRACKET

Simon Kron and Abraham Kron, New York, N. Y.

Application May 26, 1937, Serial No. 144,813

2 Claims. (Cl. 312—140)

This invention relates to new and useful improvements in an invisible screw showcase bracket.

More specifically, the invention is characterized by the provision of a pair of spaced support arms each of angular shape in cross section and arranged with their open side disposed downward and having foot portions at one of their ends by which they may be supported upon a showcase foundation and being provided with portions extended upwards at an inclination and a top horizontal portion.

Still further the invention provides for outer angle members for the support arms arranged with their open sides disposed downwards and superimposed on said support arms for clamping the edges of glass panes therebetween.

Another object of the invention is the provision of anchorage elements at spaced superimposed locations on said support arms and the angle member through which fastening elements may be engaged for fixedly holding the spaced support arms and the angle members with the panes of glass clamped therebetween.

Still further the invention provides that the spaced support arms and the outer angle members be provided with grooves into which the anchorage elements may be removably mounted to permit interchanging of the anchorage elements in the event the threads become stripped.

For further comprehension of the invention, and of the objects and advantages thereof, reference will be had to the following description and accompanying drawing, and to the appended claims in which the various novel features of the invention are more particularly set forth.

In the accompanying drawing forming a material part of this disclosure:

Fig. 1 is a perspective view of a showcase having invisible screw brackets according to this invention.

Fig. 2 is a detailed sectional view taken on the line 2—2 of Fig. 1.

Fig. 3 is an enlarged sectional view taken on the line 3—3 of Fig. 2.

Fig. 4 is a perspective view of one of the support arms and one of the angle members per se.

Fig. 5 is a sectional view taken on the line 5—5 of Fig. 4 with the members in their assembled position.

Fig. 6 is a view taken on the line 6—6 of Fig. 4, with the members in their assembled position.

Fig. 7 is a sectional view on the line 7—7 of Fig. 4.

Fig. 8 is a perspective view of a portion of Fig. 4 but showing a modification of the invention.

Fig. 9 is a sectional view taken on the line 9—9 of Fig. 8.

Fig. 10 is a sectional view taken on the line 10—10 of Fig. 9.

The invisible screw showcase bracket, according to this invention, is to be used in conjunction with a showcase in which a pair of spaced support arms 10, each of angular shape in cross section, are arranged with their open sides disposed downwards and having foot portions 11 at one of their ends by which they may be supported. Outer angle members 12 for the support arms 10 are arranged with their open sides disposed downwards and are superimposed on the support arms 10 for clamping the edges of pane of glass 13 therebetween. Anchorage elements 14 are mounted at spaced superimposed intervals on the support arms and the angle members and fastening elements 15 engage through the support arms 10 and their anchorage elements and threadedly engage the anchorage elements of the outer angle members.

The support arms 10 are mounted on a showcase foundation which consists of a counter 16 constructed of wood and having a metal covering 17 upon which the foot 11 rests. This foot 11 is provided with openings 11a through which screws 18 are adapted to pass in order to hold the support arms 10 in position upon the counter. The other ends of the supports arms 11 rest upon a rear window 19 of conventional construction and for this reason none of the details are given in this specification as this window forms no part of the invention.

The support arms 10 have portions 10a extending upwards at an inclination and continue into top horizontal portions 10b. The support arm 10 is provided with the anchorage elements 14 which are fixedly held in position by welding, brazing, or similar means so as to be integral therewith. The support arm 10 in the vicinity of the connection between the upward inclined portion 10a and the top horizontal portion 10b is provided with a reinforcing member 14a which extends between the anchorage elements 14 in this vicinity and are integrally formed therewith and fixedly attached to the support arm 10 together with the element 14 to strengthen the arm in this vicinity.

Thus it will be seen in Fig. 6 the support arm 10 and the reinforcing member 14a fill in the space between the arms of the angle support arm forming a solid construction provided with an opening 20 through which the fastening element 15 engages. The anchorage element 14 at the lower end of the upward inclined portion 10a is provided with a reinforcing member 14a which is provided with the foot 11 and which fills the space between the arms of the angular support member 10 to strengthen the bottom portion of the support arm.

The remaining anchorage elements 14 are merely integrally formed with the arms of the angular support member 10 and are provided with

the openings 20 through which the fastening elements 15 engage.

The outer angle members 12 consist of strips of angular material which are provided with anchorage elements 14 welded, brazed, or in any other manner integrally formed therewith and which are spaced at superimposed intervals with relation to the anchorage elements 14 on the support arms, and are provided with threaded openings 21 into which the ends of the fastening elements 15 are adapted to engage in order to clamp the panes of glass 13 between the angle members 12 and the support arms 10. The angle member 12 which is superimposed on the top horizontal portion 10^b of the support arm 10 is provided at one of its ends with a turned under edge portion 12^a which is adapted to engage about the edge of the top pane of glass 13^a to prevent this pane of glass from slipping from between the angle members 12 and the top horizontal portion 10^b.

The panes of glass 13 consist of a top pane 13^a clamped in position upon the top horizontal portion 10^b of the support arm 10, a front pane of glass 13^b clamped in position upon the upward inclined portion 10^a, and end panes of glass 13^c clamped in position upon the ends of the showcase against the sides of the top horizontal portion 10^b and the upward inclined portions 10^a. The rear end of the show case is closed by the window structure 19 of conventional construction.

The main feature of this invention is the support arm 10 which is provided with the upward inclined portion 10^a and the top horizontal portion 10^b against which the panes of glass 13 may be clamped after they have been set in position, and outer angular members engaged thereover which are provided with anchorage members 14 in superimposed positions with anchorage members on the support arm 10 and through which the fastening means 15 comprising screws or similar elements may be engaged for holding the support arm 10 and the angle members 12 in position with the panes of glass clamped therebetween.

According to the modification shown in Figs. 8-10 a means is provided for removably mounting the anchorage members 14' upon the support arms 10 and the angle members 12. This means consists of grooves 25 which are milled in the inner faces of the support arms 10 and the angle members 12 and which are provided with wide mouths 25^a and narrow inner ends 25^b. The anchorage elements 14' consist of small metallic members which are adapted to be placed into the wide mouth 25^a of the slots 25 and then slipped downward within the slots 25 until they engage the narrow inner portions 25^b. When they engage these narrow inner portions 25^b the fastening member 15 may be engaged therethrough for clamping the panes of glass 13 between the support arm 10 and the angle member 12. These grooves 25 have their edges arranged so that the edges of the anchorage elements 14' will engage thereagainst to prevent the anchorage elements from slipping out of the grooves when pressure is applied thereto by means of the screw or fastening means 15. In other respects this form of the invention is similar to the previous form and similar parts may be recognized by corresponding reference numerals.

The operation of this form of the invention is as follows: When the threads upon any of the

anchorage elements 14' become stripped, or other reasons, it is merely necessary to disengage the fastening element 15 from these anchorage elements 14' to permit the anchorage element 14' to be disengaged from the slot 25 through the wide mouth 25^a. Then a new anchorage element 14' may be engaged into the slot 25 through the mouth 25^a and slid to a position in which it will engage the narrow inner end 25^b for fixedly holding the panes of glass between the support arm 10 and the angle member 12 when the screw 15 has been returned to its normal position.

While we have illustrated and described the preferred embodiments of our invention, it is to be understood that we do not limit ourselves to the precise constructions herein disclosed and the right is reserved to all changes and modifications coming within the scope of the invention as defined in the appended claims.

Having thus described our invention, what we claim as new, and desire to secure by United States Letters Patent is:—

1. In a showcase, a pair of spaced support arms each of angular shape in cross section and arranged with the open side disposed downwards and having foot portions at one of their ends by which they may be supported, outer angle members for said support arms arranged with their open sides disposed downwards and superimposed on said support arms for clamping the edges of glass panes therebetween, anchorage elements mounted at spaced superimposed locations on said support arms and angle members, and fastening elements engaging through said support arms and their anchorage elements and having threads engaging the anchorage elements of said outer angle members, and means for removably mounting said anchorage elements upon said support arm and said angle members, said means comprising grooves formed on the inner sides of said support arms and said angle members and into which said anchorage elements engage, said grooves consisting of a wide mouth portion and a narrow inner end, whereby said anchorage elements may be passed through said wide mouth portion and be slid into said narrow inner portion in which they tightly fit.

2. In a showcase, a pair of angular shaped support arms having their open sides directed downwards and having openings and grooves formed on either side of said openings, outer angle members for said support arms arranged with their open sides disposed downwards and superimposed on said support arms for clamping the edges of a pane of glass therebetween and having grooves formed in the sides thereof and superimposed on the grooves in said support arms, said grooves in said support arms and said angle members having wide mouth portions and narrow inner portions, anchorage elements for said grooves being adapted to be passed through said wide mouth portions and then slid to said narrow inner portions, and fastening elements engaging through the openings in said support arms and their anchorage elements and having threads engaging complementary threads formed in the anchorage elements on said angle members for holding said angle members on said support arms with said pane of glass clamped therebetween.
